UNITED STATES PATENT OFFICE

115,144

DESIGN FOR A RESTAURANT BOOTH UNIT

Cleophas A. Deravin, New York, N. Y.

Application January 10, 1939, Serial No. 82,263

Term of patent 3½ years

To all whom it may concern:

Be it known that I, Cleophas A. Deravin, a citizen of the United States of America, residing at New York city, in the county of Bronx and State of New York, have invented a new, original, and ornamental Design for a Restaurant Booth Unit, of which the following is a specification, reference being had to the accompanying drawing, forming part thereof.

In the drawing:

Fig. 1 is a front elevation of a restaurant booth unit showing my new design; and Fig. 2 is a perspective view thereof.

The table elements shown in the drawing are integral with the restaurant booth of my new design.

I claim:

The ornamental design for a restaurant booth unit, substantially as shown and described.

CLEOPHAS A. DERAVIN.
